DESIGN FOR A LAPEL PIN OR SIMILAR ARTICLE

Max Kaplan, New York, N. Y.

Application February 4, 1942, Serial No. 105,624

Term of patent 14 years

To all whom it may concern:

Be it known that Max Kaplan, a citizen of the United States and resident of New York, in the county of Kings and State of New York, has invented a new, original, and ornamental Design for a Lapel Pin or Similar Article, of which the following is a specification, reference being had to the accompanying drawing, forming part thereof, in which,

Fig. 1 is a front elevational view of a lapel pin or similar article embodying my new design;

Fig. 2 is a rear elevational view thereof; and Fig. 3 is a development view thereof illustrating the blank from which the lapel pin is made. The characteristic features of my design reside in the portions shown in full lines.

I claim:

The ornamental design for a lapel pin or similar article, substantially as shown and described.

MAX KAPLAN.
